Marcel Boucher, New York, N. Y.

Application February 14, 1948, Serial No. 144,473

Term of patent 3½ years

(Cl. D45—19)

To all whom it may concern:

Be it known that I, Marcel Boucher, a citizen of the United States, residing at New York, in the county of Richmond and State of New York, whose post office address is 4143 Richmond Avenue, Eltingville, Staten Island, New York, have invented a new, original, and ornamental Design for a Clip or Similar Article, of which the following is a specification, reference being had to the accompanying drawing, forming part thereof.

In said drawing,

Fig. 1 is a front view of a clip or similar article, showing my new design.

Fig. 2 is a side view thereof.

Fig. 3 is a top view of the same.

I claim:

The ornamental design for a clip or similar article, as shown.

MARCEL BOUCHER.
